UNITED STATES PATENT OFFICE.

JOHN E. JOHNSON, OF MUNISING, MICHIGAN.

FLOOR-CLAMP.

1,228,214.

Specification of Letters Patent.

Patented May 29, 1917.

Application filed November 18, 1915. Serial No. 62,192.

To all whom it may concern:

Be it known that I, JOHN E. JOHNSON, a citizen of the United States, residing at Munising, in the county of Alger, in the State of Michigan, have invented certain new and useful Improvements in Floor-Clamps, of which the following is a specification.

This invention relates to improvements in floor clamps and its object is to produce a tool adapted for use in laying flooring. The tool comprises the base plate adapted to be removably secured to the wall in the room in which the flooring is to be laid or removed, a runner bar that extends approximately entirely across the room, a rack slidably carried by the runner bar and operated by a hand lever fulcrumed on the base plate, and an operating block associated with the rack. The invention will be described in detail in the following specification, its advantages more particularly pointed out in the appended claims and illustrated in the accompanying drawings which form a part 25 of said specification and in which—

Figure 1 is a side elevation of my improved floor clamp in use for laying flooring.

Fig. 2 is a plan view of the same and is taken on line 2—2 of Fig. 1.

Fig. 3 is a longitudinal sectional view through Fig. 1 with the movable parts in an altered position.

Fig. 4 is a detail view of a portion of the rack and of one operating block.

Fig. 5 is an inverted plan view of the rack shown in Fig. 4.

Fig. 6 is a section taken on line 6—6 of Fig. 3.

Fig. 7 is a top plan view of the operating block shown in Fig. 4.

Fig. 8 is a section taken on line 8—8 of Fig. 7.

Like reference characters indicate corresponding parts throughout the several views.

The reference numeral 1 denotes the base plate which is adapted to be removably secured, in any suitable manner, to the wall 2 in the room in which the flooring is to be laid. In a bracket 3 integral with the base plate 1 one end of the runner bar 4 is secured by means of the pin 5, said bar extending at right angles to the wall 2 and being operatively supported by the said bracket

and pin. A rack 6 provided with teeth 7 along its upper edge and with longitudinally extending grooves 8 on each side is slidably disposed upon the bar 4 and is formed, further, with a plurality of recesses or notches 9 arranged centrally of its under side, said notches being adapted to receive a boss 10 formed upon one operating block 11 which is formed with spaced sides 12, adapted to straddle the rack 6, and with ears 13 adapted to ride in the grooved portions 8 of said rack to support the block. The block 11, further, is formed with a depending leg 14 having a notch 15 adapted to engage with the tenon of a piece of flooring 16 to move the flooring.

A pawl 17 carried by the operating lever 18, which is fulcrumed in a bearing 19 carried by the base plate, is adapted for engagement with the teeth 7 of the block 6 to move said block in a direction away from the wall 2. The form of block just described is used to lay flooring. When the first piece of flooring is laid the next piece is placed upon the joists adjacent it and the block 11 placed so that the tenon of the piece of flooring will engage with the notched portion of the leg 14 while the boss 10 is disposed in one of the notches 9 of the rack 6; this engagement of the block and rack will temporarily retain them in fixed relation and by manually moving the lever toward the runner bar the said rack and block will be moved longitudinally of said bar thus forcing the piece of flooring into close engagement with the previously laid piece.

What is claimed is:—

1. In a floor clamp, a base plate, a runner bar carried thereby, a rack slidably arranged upon said runner bar, a block embracing and slidably connected to said rack, means carried by said block and rack whereby they may be releasably locked in operative relation, a notched leg formed integral with said block and a lever fulcrumed upon said base plate for operative engagement with said rack.

2. In a floor clamp, a base plate, a runner bar carried thereby, a rack, having longitudinally grooved sides and a notched face, slidably arranged upon said runner bar, a block formed with spaced sides to straddle said rack, ears carried by said sides and

adapted to ride in the grooved portions of said rack to support said block, a boss formed upon said block for disposition in any of the notched portions of said rack, a notched leg carried by said block and a lever fulcrumed upon said base plate for operative engagement with said rack.

Copies of this patent may be obtained for five cents each, by addressing the "Commissioner of Patents, Washington, D. C."

In testimony that I claim the foregoing as my own I have hereto affixed my signature in the presence of two subscribing witnesses. 10

JOHN E. JOHNSON.
